UNITED STATES PATENT OFFICE.

EDWARD PRICE, OF LOS ANGELES, CALIFORNIA.

TEETER-BOARD.

1,320,710.

Specification of Letters Patent.

Patented Nov. 4, 1919.

Application filed April 3, 1919. Serial No. 287,319.

To all whom it may concern:

Be it known that I, EDWARD PRICE, a citizen of the United States, residing at Los Angeles, in the county of Los Angeles and 5 State of California, have invented new and useful Improvements in Teeter-Boards, of which the following is a specification.

This invention relates to teeter-boards of that class in which the teeter-board is provided with an overbalanced or weighted end portion whereby it may be operated by one person.

It is the object of this invention to provide a teeter-board of the above character 15 embodying means whereby the weighted end portion thereof may be normally held in an elevated position and adapted to be operated and controlled from the portion of the teeter-board opposite the weighted portion to permit downward movement of said weighted portion, or to hold it against downward movement at the will of the operator.

Another object is to provide the teeter-board with means for absorbing shock and effecting a rebound action at the terminus of the downward movement of said teeter-board.

Other objects will appear hereinafter.

30 The invention is illustrated in the accompanying drawings in which:

Figure 1 is a view of the teeter-board as seen in side elevation.

Fig. 2 is a perspective view of same illustrating the manner of its operation.

More specifically 5 indicates a rockable member which may be of any suitable construction, but is here shown as consisting of a plank fitted with trunnions 6 intermediate 40 its ends which trunnions are supported in bearings 7 carried on a suitable frame 8.

One end portion of the rockable member is designed to be counter-weighted or overbalanced, and for this purpose is here shown 45 as provided with a box 9 disposed at the end of the rockable member and adapted to receive weights 10 of any suitable character, which weights act normally to maintain the overbalanced end portion of the rockable

50 members in a lowered position. Means are provided for holding the weighted end of the rockable member in an elevated position so as to dispose the underbalanced end portion of the rockable member in a lowered 55 position to permit easy mounting and dismounting. This means is here shown as

consisting of a normally dependent pivoted leg 11 which is connected to the end of the rockable member by a hinge 12 in such manner that it may swing vertically in and out 60 of its dependent position in a direction longitudinally of the rockable member. If desired, the hinge 12 may be a spring hinge so as to act to normally maintain the hinged leg in a dependent position, but ordinarily 65 the weight of the hinged leg will be sufficient to normally suspend it in a vertical position. Connected with the hinged leg is a cord 13 which passes upwardly through a guide member 14 on the box 9 and thence 70 extends rearwardly to a post 15 disposed adjacent to the unweighted end of the rockable member, but spaced from the end thereof to provide seating room.

As a means for cushioning downward 75 movement of the weighted end of the rockable member at the terminus of such movement, a spiral spring 16 is mounted on the underside of the plank beneath the box 9 and projects downwardly so as to come in 80 contact with the ground surface. This spring also serves to exert a rebound action on impact with the ground to give an initial upward impulse to the weighted end of the rockable member when in operation, thus 85 facilitating the control of the teeter by the person riding thereon. The spring 16 is carried on a block 17 disposed on the under side of the plank and arranged adjacent to the hinged leg so as to serve as a stop for the 90 latter.

In the operation of the invention sufficient weight is placed in the box to approximately counter-balance the weight of the person or rider whereupon the rider mounts the seat 95 portion of the rockable member between the post and the end thereof.

On pulling upon the cord 13 the leg 11 will be swung outwardly so as to clear the supporting surface, thus permitting rocking 100 movement of the teeter-board. On downward movement of the weighted end of the rockable member the spring 16 will strike the ground surface and act to cushion such downward movement and also act to effect 105 a rebound action as before described. On the downward movement of the opposite end of the rockable member the rider will effect return movement by upward impulse with the feet, as is common in ordinary teeter-boards; the rider and the spring thus alternately effecting continued rocking movement 110

of the teeter-board. The hinged leg is held in an elevated position during the rocking operation by the cord 13 which may, if desired, be hitched to the post 15. However, 5 the cord is usually held as in driving, and as the leg 11 is hinged, the cord may be drawn back and forth during the teetering operation.

When it is desired to discontinue movement of the teeter-board the cord is released so that the hinged leg will drop to its normal vertical position into engagement with the ground surface to hold the weighted end of the teeter-board in an elevated position.

15 While I have shown and described a specific embodiment of my invention, various changes may be made in the details of construction, though without departing from the spirit and scope of the invention as set 20 forth in the appended claims.

I claim:

1. In a teeter-board, a rockable member having a weighted and overbalanced end portion, a rebound element arranged to act 25 on the overbalanced end portion of said rockable member at the terminus of its downward movement, means for normally holding the overbalanced end portion in an elevated position, and means for releasing 30 said last named means from the other end portion of the rockable member.

2. In a teeter-board, a rockable member, a counterweight on one end thereof, means for normally holding the counterweighted end 35 of said rockable member in an elevated position, and means for releasing said last named means from the other end portion of the rockable member.

3. In a teeter-board, a rockable member having a weighted end portion, a pivoted 40 leg on the weighted portion for holding said weighted end portion in an elevated position, and means operable from the other end portion for throwing said leg in and out of an operative position.

4. In a teeter-board, a rockable member having an overbalanced end portion and an underbalanced end portion, a normally dependent hinged leg on the overbalanced end portion of said rockable member engageable 50 with a supporting surface to hold the overbalanced end portion in an elevated position, and means operable from the underbalanced end portion of said rockable member for throwing said hinged leg out of engagement 55 with its supporting surface to permit downward movement of the overbalanced end portion of the rockable member.

5. In a teeter-board, a rockable member having an overbalanced end portion and an 60 underbalanced end portion, a normally dependent hinged leg on the overbalanced end portion of said rockable member engageable with a supporting surface to hold the overbalanced end portion in an elevated position, 65 means operable from the underbalanced end portion of said rockable member for throwing said hinged leg out of engagement with its supporting surface to permit downward movement of the overbalanced end portion 70 of the rockable member, and means for absorbing shock and effecting rebound action on the overbalanced end portion at the terminus of the downward movement thereof.

EDWARD PRICE.
